UNITED STATES PATENT OFFICE.

PAUL D. BODWELL AND HENRY W. BELLows, OF WAYNESBORO, PENNSYLVANIA, AS-SIGNORS TO DECA-DISC PHONOGRAPH COMPANY, OF WAYNESBORO, PENNSYLVANIA, A CORPORATION OF PENNSYLVANIA.

RECORD HOLDER FOR TALKING MACHINES.

Application filed July 30, 1925, Serial No. 47,099. Renewed May 12, 1927.

Our said invention relates to a talking machine record holder and it is an object of the same to provide a device which shall hold a record securely in position in a manner to avoid damage to the edges or the faces of the record. This device is intended particularly for use in connection with a talking machine employing a stack of records and playing them successively but is not limited to such use.

Referring to the accompanying drawings which are made a part hereof and on which similar reference characters indicate similar parts,

15 Figure 1 is a plan of our device showing a record in position thereon,

Figure 2, a section on line 2—2 of Figure 1, and

20 Figure 3, a perspective of an element of the device.

In the drawings, reference character 10 indicates a grooved record such as ordinarily used upon talking machines of the disk type. This record is shown as being surrounded by a ring 11 of aluminum said ring consisting of a thin flat metal strip bent approximately into U-shape in section as clearly shown in Figure 2. A wire 12 provides a frame over which the strip may be bent, e. g. from a cylindrical ring, into the shape illustrated in Figure 2 after which the wire may remain in place between the flanges of ring 11 to strengthen the device. We do not, of course, limit ourselves to this method of manufacturing the device.

35 Between the sides of the ring, we provide a number of grippers 13 as shown in Fig. 3 each of which comprises a strip of spring metal having inwardly bent flanges 14 which straddle the adjacent edge of a record disk. The ring has punched-in lugs 15 which engage over a bend 16 in each respective gripper and the gripper is further bent inward at its ends as indicated at 17 and 19 to reduce friction between the gripper and the adjacent surface of the wire 12 or the ring 11. As here shown there are five grippers which number may be increased or decreased according to convenience.

50 In placing a record in the holder, it is only necessary to engage the record between

the parts 14 of one or more grippers and spring the others out after which the record is forced into the plane of the ring 11 and held in place by the grippers, each of 55 which engages with its opposed flanges 14 over opposite sides of the edge thereof so as to hold it in place. The reverse of the process described serves to dismount the record.

One important advantage of the device is 60 that it eliminates chipping of the edges of the records. Preferably also, the distance between the opposite sides 18 of the ring is such that the records may be piled in a stack with their faces free from engagement with 65 each other thus preventing any injury to the sound producing grooves and ridges of the disk, whether the records are in the machine or outside, and whether they are stacked on one another or otherwise supported.

70 It will be obvious to those skilled in the art that various changes may be made in our device without departing from the spirit thereof and therefore we do not limit ourselves to what is shown in the drawings and 75 described in the specification but only as indicated in the appended claims.

Having thus fully described our said invention, what we claim as new and desire to secure by Letters Patent, is:

80 1. A holder for disk records comprising a part surrounding the outer edge of the record, and means for resiliently holding the record and said part in position relative to each other, substantially as set forth.

85 2. A holder for disk records comprising a part surrounding the outer edge of the record, and resilient means for holding the record and said part in position relative to each other, substantially as set forth.

90 3. A holder for disk records comprising a device of greater thickness than such disk record said device adapted to be positioned about a record, and means for maintaining the record in position midway between the 95 planes of the extremities of such device to prevent injury to the face of the record, substantially as set forth.

100 4. A holding device for disk records comprising a grooved ring adapted to be positioned about a record, and resilient means in the groove arranged for engagement with

the outer edge of a record, substantially as set forth.

5. A holding device for disk records comprising a grooved ring adapted to be positioned about a record, resilient strips of metal located in the groove said strips having flanges straddling the edge of the record, and means for holding each of said

strips against movement circumferentially of the ring, substantially as set forth. 10

In witness whereof, we have hereunto set our hands at Waynesboro, Pennsylvania, this 29th day of July, A. D. nineteen hundred and twenty-five.

PAUL D. BODWELL,
HENRY W. BELLows.
